UNITED STATES PATENT OFFICE.

WILLIAM MORRIS BOWER, OF LONDON, ENGLAND, ASSIGNOR TO LINOTYPE AND MACHINERY LIMITED, OF LONDON, ENGLAND.

PRODUCTION OF ACCENTED CHARACTERS IN TYPOGRAPHICAL COMPOSING AND CASTING MACHINES.

Application filed September 2, 1925, Serial No. 54,002, and in Great Britain September 26, 1924.

This invention relates to the production of accented characters in typographical composing and casting machines such as those known commercially under the trade mark 5 "Linotype". More particularly, the invention is concerned with an improved method of forming and utilizing accents, which is especially advantageous in connection with slugs or type-bars bearing capital 10 characters in large display faces. The characters themselves occupy practically the full body width of such slugs, and consequently the presence of an accented character in a line necessitates the casting of the slug in a mould having a body of larger size than that required for an unaccented slug, unless the slug is produced with an overhang bearing the accent, in which case a modification of the slug-trimming mechanism 15 20 must be made.

In carrying out the present invention the necessity for changes such as those just referred to, are avoided by a method which involves the production of a slug bearing 25 accents alone, and afterwards associating the accent slug, or portions of it, with a slug bearing the characters, which is cast in a mould of the normal body dimension appropriate to the size of the face in use.

30 As is well known, in machines of the kind to which the invention relates, the matrices, which are assembled in line and presented to the mould for the casting of the slug, bear their characters in inverted position, 35 and are arranged for alignment at the bottom of the slug as cast with the bases of the characters presented towards the top of the slug as cast. The accent matrices, which it is proposed to use for the production of an accent 40 slug according to the present invention, differ from the just-mentioned normal arrangement in that the accents thereon are not inverted and, although also arranged to align at the bottom of the slug as cast, have 45 their bases presented towards the bottom of the slug as cast. Hence, the accents in such slug may be brought into correct relationship with the character slug irrespective of the body dimension of the mould in which 50 the accent slug is cast, as the two slugs are associated by inverting the accent slug and assembling it in the forme against the top of the character slug.

In the accompanying drawings which are

to be taken as part of this specification and 55 read therewith:—

Figure 1 is a perspective view of a matrix used in the casting, according to the present invention, of an accent-bearing slug;

Figure 2 is a perspective of a matrix used 60 in the casting of a character-bearing slug complementary to that produced from a matrix such as that shown in Figure 1;

Figure 3 is a view of a slug having accent 65 faces produced from matrices such as shown in Figure 1;

Figure 4 is a view similar to Figure 3, of a slug having character faces produced from matrices such as shown in Figure 2, and 70

Figure 5 is an example of printing from the two slugs shown in Figures 3 and 4.

The matrix 1 shown in Figure 1 is one for producing a circumflex accent, while the matrix 2 shown in Figure 2 is for producing 75 the character A. By comparing these two figures it will be seen that whereas character matrices 2 have their formative cavities 3 so disposed as to cast the characters 4 in inverted position on the slug 5 (Figure 4) 80 and are arranged to present the bases of the characters towards the top of said slug as cast, which is the ordinary procedure, accent matrices 1 have their formative cavities 6 arranged to cast the accents 7 on the slug 8 85 (Figure 3) with their feet presented towards the bottom of the slug as cast and of a body dimension not exceeding that of the slug itself.

It will therefore be evident that whatever 90 may be the body dimension of a slug 8 or the mould cavity in which it is cast (and two different thicknesses of slug are indicated in Figure 3, one in full lines and the other in both full and dotted lines) the accents 7 on said slug can always be brought 95 into correct relationship with the respective characters 4 on a character-bearing slug 5, by inverting the accent-bearing slug and thereafter assembling it in the forme with the feet of the accents facing towards the top of the slug 5, so that the conjunction of two slugs such as those represented in Figures 3 and 4 would serve to produce a line 100 of accented display printing such as is shown in Figure 5.

Figures 3 and 4 show the slugs 5 and 8 in the positions in which they are cast in 105

the mould. From an inspection of these figures it will be seen that whereas the matrices for producing the characters 4 are assembled in the order in which said characters are to appear in print, the matrices for producing the accents 7 on a complete slug to be associated with the character-bearing slug, must be assembled in the reverse order owing to the fact that the slugs 8 bearing those accents have to be reversed for association with the respective character-bearing slugs 5. It will be understood however, that it is within the scope of the invention to associate with the character-bearing slug, portions of an accent-bearing slug, in which case the order of assemblage of the accent matrices would be immaterial.

Having described my invention, I declare that what I claim and desire to secure by Letters Patent is:—

1. The method of producing accented characters in a typographical composing and casting machine consisting in casting the characters and accents relatively inverted on respectively different slugs, the characters and accents being aligned at relatively different sides of the respective slugs.

2. The method of producing accented characters in a typographical composing and casting machine consisting in casting the characters and accents relatively inverted on respectively different slugs, the characters having their feet presented towards the top of the slug as cast and the accents having their feet presented towards the bottom of the slug as cast.

3. A printing slug having an accent face aligned at its foot, and a body dimension not exceeding that of the slug itself.

4. In or for a slug casting machine two sets of matrices, those of one set having formative cavities which are adapted to form character faces occupying practically the full body width of the slug on which they are produced, and those of the other set having formative cavities which are adapted to form accent faces, these formative cavities in the respective sets of matrices being rela-

tively inverted, and arranged for alignment at respectively opposite sides of the slug. 50

5. A printing form including two complementary slugs, one having an accent face aligned at the foot of said face, and a body dimension not exceeding that of the slug itself, and the other having a character face aligned at the head of said face and occupying practically the full body width of the respective slug, said slugs being juxtaposed with the accent face and character face mutually registering with each other. 60

6. A printing form comprising two complementary slugs, one bearing a character face aligned at its head and presenting its foot toward the top of the slug as cast, and the other bearing an accent face aligned 65 at its foot and presenting said foot toward the bottom of the slug as cast, the two slugs being arranged with the two sides along which their faces are aligned in contact and with the accent and character faces mutually registering with each other.

7. The method of producing accented characters in a slug casting machine, which consists in providing two sets of matrices, one set bearing inverted character formative cavities and the other set bearing uninverted accent formative cavities, casting different slugs from separate lines composed of matrices from the different sets so as to produce complementary slugs, one with a character face corresponding to one set of matrices aligned at the bottom of the slug as cast but with the foot of said face presented toward the top of the slug as cast, 75

and the other with an accent face corresponding to the second set of matrices also aligned at the bottom of the slug as cast but with its foot presented toward the bottom of the slug as cast, and thereafter making up the printing form by inverting the slugs relatively to each other to bring the character and accent faces in mutual registration. 80

In testimony whereof I have affixed my signature hereto.

WILLIAM MORRIS BOWER.
